UNITED STATES PATENT OFFICE.

GUSTAV EKLUND, OF NEW YORK, N. Y., ASSIGNOR TO THE DRESSEL RAILWAY LAMP WORKS, A CORPORATION OF NEW YORK.

LAMP-BURNER.

1,109,327.

Specification of Letters Patent.

Patented Sept. 1, 1914.

Application filed October 6, 1910. Serial No. 585,554.

To all whom it may concern:

Be it known that I, GUSTAV EKLUND, a citizen of the United States, residing at the city of New York, borough of the Bronx, in 5 the county and State of New York, have invented certain new and useful Improvements in Lamp-Burners, of which the following is a full, clear, and exact specification.

My invention relates to improvements in 10 lamp burners of the type known as long time burners, and the same has for its object to provide a simple, efficient and reliable burner capable of producing a large flame without the use of a chimney.

15 Further said invention has for its object to provide a burner in which the flame is enlarged to such size in the focus of the lens, as to emit toward the lens a maximum of light rays with a minimum consumption of 20 oil.

Further, said invention has for its object to provide a burner in which a considerable number of separate air jets are jetted in a variety of angles into the lower or blue portion of the flame.

Further, said invention has for its object to provide a burner in which the ascending air currents or jets are retarded in their circulation or movement in order to produce a 30 perfect combustion of the gases, and produce a thick white flame just above the spreader, and at the smallest distance possible above the wick tube.

To the attainment of the aforesaid objects 35 and ends my invention consists in the novel details of construction, and in the combination, connection and arrangement of parts hereinafter more fully described and then pointed out in the claims.

40 In the accompanying drawings forming part of this specification, wherein like numerals of reference indicate like parts, Figure 1 is an enlarged top view showing one form of burner constructed according to, 45 and embodying my said invention; Fig. 2 is a section taken on the line 2—2 of Fig. 1, and Fig. 3 is a section taken on the line 3—3 of Fig. 1.

In said drawings 5 designates the base 50 portion of the burner which is provided at its lower reduced end with a screw-threaded portion 6, and at its upper end with a gallery or upwardly flaring flange 7 having a dome-shaped base 8. Said dome-shaped 55 base is secured at the junction of its edge

with said gallery or flange 7 to the upper edge of the base portion 5. The gallery or flange 7 is provided at its upper edge with a rounded rim or bead 9 and below said rim or bead with circular apertures 10, and 60 openings 10^a respectively.

11 denotes a flat wick tube which is centrally disposed within the base portion 5, and has its lower end projecting slightly below the bottom of said base portion 5. The 65 upper end of said wick tube 11 terminates in a horizontal plane above the upper edge of the gallery or flange 7, and is secured adjacent to its upper end to the dome-shaped base 8. From one side of the base portion 5 70 extends a sleeve 12 in which is supported a wick raising shaft 13 provided at its inner end with star wheels 14, 14 extending into the wick tube 11.

15 denotes the flame spreader comprising 75 two curved side plates or members 16, 16 united at their opposite ends by upwardly and outwardly extending end members 17, 17. The side plates or members 16, 16 have their upper edges arranged parallel with the 80 broader edges of the wick tube 11, and in about a horizontal plane with the upper end of said wick tube. The said flame spreader is supported in position by two oppositely arranged arms 18, 18 formed integral with 85 the end members 17, 17. The said arms 18, 18 extend upwardly and outwardly and are folded back upon themselves, and then bent outwardly and downwardly, and their extremities passed through recesses in the upper edge of the flaring flange 7, and clamped around the rim or bead 9 thereof. The side and end members of the flame spreader are provided with numerous comparatively large apertures 19, 19^a, respectively, which 95 serve to conduct a large number of separated air jets to a point just above the upper end of the wick tube and which impinge against the base of the flame.

By making the side members curved 100 transversely and providing the same with apertures as shown and described, the air currents are caused to enter through the same and be projected inwardly at a variety of angles toward the upper end of the wick 105 tube and the base of the flame. At the same time, certain of the air jets or streams passing downwardly through the uppermost apertures will meet with other of the air jets passing through the lower apertures 110

in a more horizontal direction, and in meeting with the same cause said air jets to be retarded, but still kept in motion so that a continual supply of air is brought into contact with the flame, and the proper combustion of the gases maintained.

In the operation of the lamp the flame spreader serves as an automatic control for maintaining the flame at the desired height.

- 10 As is well known, owing to the difference in the external atmosphere the hot air of the up feed flows faster as the heat increases, and this tends to draw the flame upward. This will also produce an increase in the speed of flow of the air jets entering through the side members of the flame spreader, but as certain of these apertures cause the air currents to pass therethrough in a more or less downward direction, they are caused to 15 impinge upon and retard the speed of the upwardly passing main air currents, and thus prevent or reduce to a minimum the tendency of the flame to crawl or climb upward, which would otherwise occur as soon 20 as the parts become heated.

Having thus described my invention, what I claim and desire to secure by Letters Patent is:

- 25 1. In a lamp burner, the combination of a wick tube with a flame spreader comprising a pair of inwardly and upwardly curved longitudinal plates secured together at their opposite ends and provided with perfora-

tions, said plates having their lower edges substantially in alignment with the upper edge of said wick tube, and the perforations in said plates arranged to project the incoming jets of air against the base of the flame and retard the upgoing currents of air entering said flame spreader from below, substantially as specified.

2. In a lamp burner, the combination of a wick tube with a flame spreader comprising a pair of oppositely arranged upwardly and inwardly curved, longitudinal plates, a pair of upwardly and outwardly inclined members arranged at the opposite ends of said longitudinal plates and means for supporting said flame spreader in position with its lower edge in the same horizontal plane with the upper edge of said wick tube, the said longitudinal plates being provided with perforations whereby to project a plurality of incoming jets of air downwardly and inwardly toward the wick tube whereby to retard the upgoing currents of air entering said flame spreader from below and enveloping said wick tube, substantially as specified.

Signed at the city of New York, in the county and State of New York, this 30th day of June nineteen ten.

GUSTAV EKLUND.
